(57) **CLAIM**

The ornamental design for a bottle, as shown and described.

DESCRIPTION

FIG. 1 is a top front and right side perspective view of a bottle; FIG. 2 is a front elevational view thereof, the rear elevational view being a mirror image;

FIG. 3 is a left side elevational view thereof;

FIG. 4 is a right side elevational view thereof; and,

FIG. 5 is a top plan view thereof.

The broken lines showing a thread on the pour spout in FIGS. 1-5 and the broken lines showing multiple small circular shapes on the sidewall the front, left side, and right side elevational views in FIGS. 1-5 are included for the purpose of illustrating environmental structure and form no part of the claimed design. It is noted here that each unclaimed circular shape is made up of two concentric circles in broken lines and the entire area within each of these outermost unclaimed circles is illustrating environmental structure and forms no part of the claimed design.
